PAPER MAKING MACHINE

Nickolas J. Niks, Munising, Mich.

Application January 25, 1934, Serial No. 708,198

26 Claims.

(Cl. 92—44)

This invention relates to improvements in paper making machines, and has for its object to provide, in connection with a stock box, a breast roll which projects into one corner of the box and forms a part thereof.

It is an object of this invention to provide, in connection with a stock box, a breast roll which projects into one corner of the box and supports a wire netting onto which the stock is to be distributed, elevated and transported horizontally.

It is an object to provide, in connection with a stock box, a scraper extending from the bottom of the box to engage a breast roll substantially on a line with the horizontal radius of the roll so that as the stock is fed onto a wire screen supported and moved thereby, the stock will be elevated and transported from the box in a substantially horizontal direction.

It is also an object of the invention to provide, in connection with paper stock feeding means, a pair of adjustable slices for regulating the distribution of stock upon a wire screen.

It is also an object to provide, in connection with a stock box, rotary drum stirrers in which the central part of each stirrer will rotate in a direction opposite the peripheral part thereof, or in the same direction at a different speed.

These and other advantages will appear from the following description taken in connection with the drawings.

Referring to the drawings:

Figure 1 is a vertical, longitudinal section through a paper making machine.

Figure 2 is a vertical section through the feed roll and the parts of the paper machine adjacent thereto, showing a modified form of drum stirrer in which the central part of each drum will move at a speed different from the speed of the peripheral part.

Figure 3 shows a transverse section of the scraper.

Figure 4 is a top plan view of one side of the machine.

Figure 5 is a section on the line 5—5 of Figure 1.

Figure 6 is a section on the line 6—6 of Figure 1.

The stock from which the paper is made is contained in a box having a floor or bottom 1, sides 2, a rear not shown, and a front wall 3, adjustably supported between the side walls, which are held in proper position with relation to the front wall by means of transverse rods 2a. The front wall is supported so that it may be adjusted forwardly and rearwardly to a lim-

ited extent by means of screws 4, one at each side of the box operated by a hand wheel 5 and supported by a bracket 6 extending inwardly from the side wall.

Extending across from one side wall to the other is a shaft 7, suitably supported at its ends on some fixed part of the front wall. This shaft is provided at each end, adjacent the side wall, with a gear 8 surrounding the shaft and projecting into a pocket 9 formed in the front wall. The gear 8 meshes with a vertically disposed worm 10, which has on its upper end a handle 11 by which the worm is rotated for rotation on the shaft 7. On the shaft 7 there is a plurality of eccentrics 12 around which there is a loop member 13, which has extending therefrom a threaded shaft 14. Each eccentric projects into a pocket formed in the front wall, similar to the pocket 9 and likewise designated by the numeral 9.

There is also supported by the front wall a shaft 15 for each shaft 14 and connected thereto by a threaded sleeve 16, which is rotated by a hand wheel 17. By means of the hand wheels 17 the shafts 14 and 15 may be adjusted with relation to each other. The lower ends of the shafts 15 have thereon a slice 18. This slice extends transversely of a wire netting 23 supported on a breast roll 20 at one end of the wire netting, while the other end of the wire netting is supported by a similar roll, not shown. For the purpose of holding the shafts 15 in proper relation to the front wall there is provided for each shaft 15 a clamp member 19, in the form of a bolt with a nut thereon. The breast roll 20 is supported by means of a shaft 21 on a frame 22. The wire netting is supported adjacent the breast roll 20 by means of a plurality of tube rollers 24 suitably supported in bearings provided therefor in the frame 22.

Between the front edge of the floor of the stock box and the breast roll is a space filled by means of a scraper 25, composed of rubber with a metal plate 26 embedded therein to give to the scraper proper rigidity. The front part 27 of the scraper has no metal plate therein and engages the wire netting on the breast roll in substantially horizontal alignment with the horizontal radius of the breast roll.

As this breast roll rotates clockwise the scraper cleans the surface of the wire supported and moved thereby, and also provides a slight pocket so that the amount of surface of the wire in contact with the stock is increased, and also so that any wear on the edge of the scraper is compensated by a tendency of the edge of the scraper to move upwardly, due to the rotation.

of the breast roll and the movement of the wire screen thereon. By this means there is assured a close engagement between the scraper and the wire netting on the breast roll.

5 In the stock box is a plurality of stirring drums 28. These drums 28 have holes 29 in the peripheries thereof, and the drums are supported by means of radially disposed plates 30 on an axle 32. Each radially disposed plate has therein a plurality of holes 31 so that the stock may pass through the holes and be thoroughly stirred and agitated.

10 In the form shown in Figure 2 the drums and the radially disposed plates are supported on the shafts so they may rotate at different speeds, or the plates may rotate in a direction opposite to that of the periphery of the drum. In this form the independently rotated radial plates are indicated by the numeral 33 and have holes 34 therein through which the stock may pass for the purpose of being agitated. These plates are supported for rotation on the shafts by means of hubs 35. In front of the front wall is a second auxiliary stock chamber formed by side walls 36 and a front wall 37, which does not extend all the way to the wire netting.

15 There is provided a transversely extending shaft 38 supported by means of loops 39 on standards 40. The loops 39 have in each end a slot 30 41 for receiving a bolt 42 by which the loops may be adjusted longitudinally of the paper machine so that the shaft 38 may be adjusted. To one end of the shaft 38 is attached one end of an arm 43. The other end of this arm may be 25 adjusted by means of a shaft 44 provided with a hand wheel 45 for that purpose. By operating the shaft 44 the arm 43 is moved at one end so that the shaft 38 will rock or rotate on its supports. It is to be understood that there may 30 be two of these arms, one at each end of the shaft 38.

20 To this shaft 38 there is attached a plurality of arms 46, each arm being attached at one end to the shaft while its other end is connected to an angle iron 47 in any suitable manner. These arms 46 and the angle iron attached thereto support the rear end of an apron 48, which is attached at its front edge 49 to some suitable part of the shaft 38 by means of stay bolts 50. 25 Each of these bolts is attached at one end to the rear of the apron, while its other end is connected to the angle iron by means of nuts 51.

30 Extending downwardly from the rear end of the apron is a plate 52, which has on its upper edge a plate 53 adapted to engage the lower edge of the front wall 37. Just in front of the plate 52 and extending downwardly from the rear end of the apron to a point slightly below the lower edge of the plate 52 is a slice 54. The stay bolts 50, the plate 52 and the rear end of the apron are joined by means of plates 55 and a transversely extending rod 56.

35 Extending from the scraper 25 along the periphery of the breast roll, and forwardly along the top of the wire screen at each edge thereof, is a guide 57 adapted to guide the stock as it moves forwardly on the wire screen. These guides terminate adjacent deckel straps 58, one at each edge of the wire screen and supported by rollers 59. These rollers are supported and operated in any suitable manner. The slices may be adjusted independently of each other. The slice immediately above the breast roll may be 40 adjusted from end to end by means of the hand

wheels 17, and it may be adjusted as a whole by means of the eccentrics on the shaft 7.

The slice 54 may be adjusted independently of the slice 18. In operation the slice 54 is usually spaced from the wire netting a shorter distance 5 than the slice 18, but the slice 54 may be elevated out of operative position so it can be used. By means of the slice 54 and the side walls 36 there is provided an additional stock box in which the stock may accumulate between the two walls. 10

I desire to comprehend within my invention such modifications as may be embraced within my claims and the scope of my invention.

Having thus fully described my invention, what I claim as new and desire to secure by Letters 15 Patent, is:

1. In a method of paper manufacture, drawing a wire along one side of a body of paper stock upwardly and horizontally to distribute the stock thereon, agitating the stock in a plurality of zones 20 while it is being deposited upon the wire, and thereafter regulating the depth of distribution of the stock and draining the water from the stock.

2. In a method of manufacturing paper, moving a wire in engagement with the body of the stock, and agitating the stock in a plurality of zones while it is being deposited upon the wire surface, one of said agitating zones being adjacent the point of departure of said wire and the layer deposited thereon from the body of the stock, 25 and the stock.

3. In a method of manufacturing paper, moving a wire in engagement with the body of the stock, agitating the stock in a plurality of zones while it is being deposited upon the wire surface, 35 one of said agitating zones being adjacent the point of departure of said wire and the layer deposited thereon from the body of the stock, and elevating the stock on the wire during distribution.

4. In a method of manufacturing paper, moving a wire in engagement with the body of the stock, agitating and distributing the stock over the wire surface, elevating the stock on the wire 45 during distribution, and distributing the stock and regulating its depth while it is moving horizontally.

5. In a method of manufacturing paper, moving a wire in engagement with the body of the stock, agitating and distributing the stock over 50 the wire surface, elevating the stock on the wire during distribution, and distributing the stock and regulating its depth while it is moving horizontally by successive distribution operations.

6. In a method of manufacturing paper, moving a wire in engagement with the body of the stock, agitating and distributing the stock over the wire surface, elevating the stock on the wire during distribution, and distributing the stock and regulating its depth while it is moving horizontally by successive distribution operations, 55 and draining the water from the stock after the stock has been laid and distributed on the wire.

7. In a paper making machine, a stock box, a breast roll mounted in one corner thereof, a wire 60 passing over the breast roll passing through one corner of the stock box from the bottom to one wall thereof, and an agitator arranged in proximity to said wire to agitate the material deposited thereon.

8. In a paper making machine, a stock box, a breast roll mounted in one corner thereof, a wire 65 passing over the breast roll through one corner of the stock box from the bottom to one wall thereof, an agitator arranged in proximity to said 70

wire to agitate the material deposited thereon, and slice means mounted over the wire exterior of the box.

9. In a paper making machine, a stock box, a breast roll mounted in one corner thereof, a wire passing over the breast roll through one corner of the stock box from the bottom to one wall thereof, an agitator arranged in proximity to said wire to agitate the material deposited thereon, and slice means mounted over the wire exterior of the box, said slice means comprising a pair of spaced slices arranged at different elevations above the wire.

10. In a paper making machine, a stock box, a breast roll mounted in one corner thereof, a wire passing over the breast roll through one corner of the stock box from the bottom to one wall thereof, and slice means mounted over the wire exterior of the box, said slice means comprising a pair of spaced slices arranged at different elevations above the wire, the first of said slices being closely adjacent the exit of the wire from the stock box and the second being spaced therefrom.

11. In a paper making machine, a stock box, a breast roll mounted in one corner thereof, a wire passing over the breast roll through one corner of the stock box from the bottom to one wall thereof, and slice means comprising a pair of spaced slices arranged at different elevations above the wire, the first of said slices being closely adjacent the exit of the wire from the stock box and the second being spaced therefrom over the first tube roll.

12. In a paper making machine, a stock box, a breast roll located with a portion of its periphery in one corner thereof, a wire passing over said breast roll adapted to pass upwardly and horizontally in engagement with the stock, an agitator in close proximity to said breast roll to agitate the material deposited on said wire, and distribution means in the stock box for distributing the stock over the wire.

13. In a paper making machine, a stock box, a breast roll located with a portion of its periphery in one corner of the box, a wire passing over the roll through the box, an adjustable slice mounted on the front wall of the box above the roll and the wire, and a second adjustable slice above the wire outside the box in advance of the first slice.

14. In a paper making machine, a stock box, a breast roll located with a portion of its periphery in one corner of the box, a wire passing over the roll through the box, an adjustable front wall for the box above the roll and spaced from the wire, a slice on said wall, and means on said wall for adjusting the slice.

15. In a paper making machine, a stock box, a breast roll located with a portion of its periphery in one corner of the box, a wire passing over the roll through the box, an adjustable front wall for the box above the roll and spaced from the wire, a flexible slice on said wall, means on the wall to adjust the slice as a whole, and means to adjust different parts of the slice.

16. In a paper making machine, a stock box, a breast roll located with a portion of its periphery in one corner of the box, a wire passing over the roll through the box, an adjustable front wall for the box above the roll and spaced from the wire, a flexible slice on said wall, means on the wall to adjust the slice as a whole, and means to adjust different parts of the slice, said last-named means forming parts of the first-named means.

17. In a paper making machine, a stock box, a breast roll having a wire thereon to take stock from the box and transport it, a pair of stirring drums in the box adjacent the breast roll, said stirring drums being arranged to agitate the material as it is deposited on the wire, and means to distribute the stock over the wire, said means comprising a front wall for the box spaced from the wire, a slice on the lower edge of the wall and means to adjust the slice to and from the wire. 10

18. In a paper making machine, a stock box, a breast roll having a wire thereon to take stock from the box and transport it, a pair of stirring drums in the box adjacent the breast roll, said stirring drums being arranged to agitate the material as it is deposited on the wire, and means to distribute the stock over the wire, said means comprising a front wall for the box spaced from the wire, a slice on the lower edge of the wall and means to adjust the slice to and from the wire, 15 said last-named means including a shaft having eccentrics thereon, straps around the eccentrics and adjustable members connecting the straps to the slice.

19. In a paper making machine, a wire, a stock box having therein a pair of perforated drums arranged to agitate the stock as it is being deposited on the wire, and means to distribute the stock on the wire, said means consisting of a plurality of spaced slices and means to adjust the 30 slices.

20. In a paper making machine, a stock box, a breast roll located in one corner of the box so that the bottom of the box is substantially in line with the axis of rotation of the roll, and mixing 35 drums in the box adjacent the roll, each drum comprising a perforated periphery and radially disposed perforated plates.

21. In a paper making machine, a wire, a stock box, a breast roll located in one corner of the box 40 so that the bottom of the box is substantially in line with the axis of the roll, and a pair of mixing drums in the box adjacent the roll, each drum consisting of a shaft, a plurality of radially disposed perforated plates mounted on the shaft and 45 a perforated peripheral member on the shaft about the plates.

22. In a paper making machine, a stock box, and stirring drums in the box, each drum consisting of a shaft, a perforated peripheral member on the shaft, a sleeve rotatably mounted on the shaft and radially disposed perforated plates 50 on the sleeve in the peripheral member.

23. In a paper making machine, a stock box, a breast roll in one corner of the box, and stirring 55 drums in the box slightly spaced from each other, the breast roll and from the bottom of the box, each drum consisting of a perforated peripheral member and radially disposed perforated plates mounted in the drum for rotation independently 60 thereof.

24. In a paper making machine, a stock box, a breast roll in one corner of the box, and stirring drums in the box slightly spaced from the breast roll, from each other and from the bottom of the 65 box, each drum consisting of a perforated peripheral part and members in the peripheral member movable independently thereof.

25. In a paper making machine, a stock box, a breast roll mounted in one corner of the box, a 70 yielding seal between the bottom of the box and the roll, a wire on the roll, a slice adjustably mounted in the box above the roll, and stirring drums in the box between the slice and the bottom and adjacent the roll.

26. In a paper making machine, a stock box, a breast roll mounted in one corner of the box, a yielding seal between the bottom of the box and the roll, a wire on the roll, a slice adjustably mounted in the box above the roll, and stirring drums in the box between the slice and the bottom

and adjacent the roll, each drum consisting of a supporting perforated member on the shaft and a peripheral member on the shaft around the perforated member, said perforated member being movable independently of the peripheral member. 5

NICKOLAS J. NIKS.
